UNITED STATES PATENT OFFICE.

ARTHUR S. HUNTINGTON, OF OMAHA, NEBRASKA.

JAR HANDLE AND METHOD OF PRODUCING SAME.

Application filed April 15, 1926. Serial No. 102,161.

This invention relates to an improvement in jar handles adapted to be used upon jugs, jars or other receptacles having apertured lugs for receiving the handles or parts there-
5 of, and has for one of its objects to provide handles consisting of few and simple parts so that they may be economically manufactured. Another object is to provide such a construction that the handles may be con-
10 veniently produced and applied to the receptacles and that when applied will resist stresses to advantage so that disarrangement of parts or removal from the lugs will be prevented. The invention includes the
15 product and also the manner or method of production.

With the foregoing objects in view and others to be mentioned the invention presents a novel and useful construction, com-
20 bination and arrangement of parts as described herein and claimed and as illustrated in the accompanying drawings, wherein,—

Fig. 1 is a side view showing a pair of metallic strands employed. Fig. 2 is a view showing a part of a storage jar with the handle applied thereto, the lug of the jar and the holder or sleeve for the handle being in section. Fig. 3 shows an end view
30 of the handle and a part of the jar, the latter being in section. Fig. 4 shows a side view of a jar provided with the handles. Fig. 5 is a side view, partly in section, of a tubular holder, these being employed for
35 mountings in the lugs of the jar and sleeve of the handle.

Referring now to the drawings in which like reference numerals indicate like parts in the several views, the invention is shown
40 and described in connection with a storage jar 6 provided at its opposed sides with hollow or apertured lugs 7. While I have shown a specific form for the lugs, this feature is not important, and the present in-
45 vention may be used in connection with any kinds of jars or other receptacles provided with lugs adapted to receive the rectilinear end-portions of the wire strips or metallic strands to be described.

50 Numerals 8 indicate a pair of hollow hand-holds or sleeves, and for each jar-handle I provide a pair of wire strips or metallic strands 9 each being bent near its ends to provide outwardly projecting loops
55 10 and 11 having approximately rectilinear,

inwardly-projecting end-portions 12 and 13, and bent midway between the loops 10 and 11 to provide an inwardly-projecting loop 14.

Numerals 15 indicate a pair of metallic, 60 tubular holders which are disposed in the apertures of the lugs 7 and sleeves 8. These holders or sheaths are not new but have been in general use for preventing injury or undue wearing away of parts and, in a manner, operate to reinforce the lugs and sleeves. In the present instance these tubular holders 15 may be used if desired or may be dispensed with, depending upon the weight or size of the jars. 70

After the metallic strands have been bent to the forms mentioned, the parts may be assembled. In operation, the end-portions 12 of the loops 10 are inserted in the respective ends of the sleeve 8 and, coincidently 75 therewith, the end-portions 13 of the loops 11 are inserted in the respective ends of the lugs 7, and by any suitable means, the loops 10 together with the sleeve 8 are swung in a circle, the result being that the two 80 strands at the ends of the inwardly-projecting loops 14 will be moved about each other and intertwined and will be maintained in linked relation as shown in Fig. 2 of the drawings. 85

It will be appreciated that the linking together of the two loops 14 as mentioned may be quickly accomplished and that removal of the end-portions 12 and 13 from the sleeve and lug will be prevented. Also it 90 is obvious that when lifting a jar by use of the handles, as described, any stresses tending to separate the loops 14 from each other will be adequately resisted since they are disposed in hooked or entwined relation. 95

From the description of operation it will be seen that the invention includes the method of making the product as well as the product itself. It is obvious that, to attempt a separate mounting for the terminals 100 12 or 13 in the sleeve 8 or lug 7, after the loops 14 have been hooked together would be quite impossible or at least would not be practical, but the operation above outlined, while simple, is effective and satisfactory. 105

By referring to Fig. 1 of the drawings it will be seen that the terminals 12 and 13 of the strands, and which project inwardly with reference to each other, are not disposed in alignment, and this is a desirable 110

feature so that said terminals will be pressed firmly against the tubular holders 15 after the parts have been assembled as shown in Fig. 2 of said drawings.

5 While I have described construction in detail I do not wish to be understood as limiting myself in this respect, and changes in form, size, proportion and minor details may be made, as found to be of advantage, 10 said changes being determined by the scope of the invention as claimed.

I claim as my invention,—

1. In a handle for a jar having an apertured lug, a sleeve providing a hand hold, 15 a pair of opposed strands bent near their respective ends to provide rectilinear terminal portions for engaging in said lug and said sleeve, said strands intermediate their rectilinear terminal portions being swung

about each other approximately 360 degrees 20 into intertwined relation.

2. In a handle for a jar having an apertured lug, a sleeve for a hand hold, a pair of metallic strands each being bent near its ends to provide a pair of outwardly projecting loops and bent midway between its ends to provide an inwardly projecting loop, 25 said strands being adapted to be disposed in opposed relation with their respective end portions projecting toward each other with- 30 in the sleeve and lug, said sleeve and loops adjacent to the sleeve being swung 360 degrees for intertwining said inwardly projecting loops.

In testimony whereof, I have affixed my 35 signature,

ARTHUR S. HUNTINGTON.
